METHOD OF INHIBITING THE CLOUDING OF
LIQUID SOAP DURING STORAGE IN GLASS
CONTAINERS

Harry L. Roschen, Maywood, Ill., assignor to Industrial Patents Corporation, Chicago, Ill., a corporation of Delaware

No Drawing. Application December 24, 1938,
Serial No. 247,643

5 Claims. (Cl. 252—109)

This invention relates to liquid soap preparations.

Liquid soap preparations, such as shampoos, when stored and held in glass containers become cloudy after standing for several months. This is generally true regardless of the soap composition and concentration and in spite of the fact that care is used in preparing a clear liquid soap before transferring the soap into the storage containers or bottles. The cloud is readily dispersed in the liquid by a slight movement of the liquid and imparts to the liquid soap a cloudy appearance.

One of the objects of this invention is to inhibit the formation of a precipitate in liquid soap preparations which are to be stored in glass containers.

The present invention contemplates the addition of a small amount of a hexametaphosphate to the liquid soap preparation.

Liquid soaps generally consist of an aqueous solution or a dilute alcohol-aqueous solution of a potassium salt of the fatty acids derived from cocoanut oil. Sodium salts of oleic acid or similar liquid acids are also employed in the preparation of liquid soaps. These liquid soap preparations generally contain from 15 per cent to 30 per cent soap.

In the present invention, hexametaphosphate is employed to inhibit the formation of the cloudy precipitate in clear liquid soap stored in glass containers. Other materials such as sulphonated higher alcohols, rosin potash soap and triethanolamine soap are unsatisfactory for the purposes of my invention.

In practicing my invention a solution of soap is prepared containing the desired amount of soap. The liquid soap preparation is then held for several days and the suspended solid matter filtered to form a clear liquid soap. A small amount of a water soluble hexametaphosphate, for example, sodium hexametaphosphate is then dissolved in the liquid soap preparation, the amount of the hexametaphosphate being based upon the amount of soap in the liquid preparation. The resulting liquid soap preparation may be stored and held in glass containers without the development of the usual cloudy precipitate.

The table which follows illustrates the inhibiting effect of the addition of small amounts of sodium hexametaphosphate to liquid soap preparations when stored in commercial types of soft glass containers. The liquid soap was prepared by dissolving soap in water and holding the solution at a temperature of from 40 degrees to 45

degrees F. for two days. The solution was then filtered to remove all suspended solid matter and to thereby clarify the solution. The solution prepared contained approximately 23 per cent soap.

Samples were then prepared by dissolving in portions of the clear soap solution, 1 per cent and 2 per cent sodium hexametaphosphate, the amount of hexametaphosphate being based upon the total soap content of the solution. Portions of the soap preparation containing soap solution only, soap solution containing 1 per cent sodium hexametaphosphate and soap solution containing 2 per cent of sodium hexametaphosphate were placed in common glass containers and stored for a period of thirty-three (33) weeks, and the samples examined periodically. The commercial containers employed in the tests included both white and green glass. At the end of thirty-three (33) weeks all of the control samples were very cloudy. These samples contained no sodium hexametaphosphate. The samples containing the inhibitor were slightly cloudy at the most, most of them being practically clear.

		7 weeks	16 weeks	33 weeks
25	Test No. 1: Control (no hexameta-phosphate).	Clear	Clear	Very cloudy.
	1% hexametaphosphate.	do	do	Very sl. cloudy.
	2% hexametaphosphate.	do	do	Do.
30	Test No. 2: Control	do	do	Very cloudy.
	1% hexametaphosphate.	do	do	Practically clear.
	2% hexametaphosphate.	do	do	Do.
35	Test No. 3: Control	do	do	Very cloudy.
	1% hexametaphosphate.	do	do	Slightly cloudy.
	2% hexametaphosphate.	do	do	Practically clear.
40	Test No. 4: Control	do	do	Very cloudy.
	1% hexametaphosphate.	do	do	Slightly cloudy.
	2% hexametaphosphate.	do	do	Practically clear.
45	Test No. 5: Control	do	do	Very cloudy.
	1% hexametaphosphate.	do	do	Slightly cloudy.
	2% hexametaphosphate.	do	do	Practically clear.
50	Test No. 6: Control	do	do	Cloudy.
	1% hexametaphosphate.	do	do	Practically clear.
	2% hexametaphosphate.	do	do	Do.

I claim:

1. The method of inhibiting the clouding during storage in glass containers of liquid soaps of the class consisting of liquid potassium soaps and liquid sodium soaps of liquid higher fatty acids, which comprises separating any insoluble calcium and magnesium compounds from the soap solution, and thereafter adding to the clear solution about 1% to 2% of a water soluble alkali metal hexametaphosphate based on the total soap content of the solution.

2. The method of inhibiting the clouding of liquid potassium soaps during storage in glass containers which comprises removing the insoluble calcium and magnesium compounds by filtering the soap solution, and thereafter adding to the soap solution about 1% to 2% of a water soluble alkali metal hexametaphosphate based on the total soap content of the solution.

3. The method of inhibiting clouding of liquid potassium cocoanut oil soap during storage of the soap in glass containers which comprises removing the insoluble calcium and magnesium compounds by filtering the soap solution, and thereafter adding to the soap from 1% to 2% sodium hexametaphosphate, based upon the total soap content of the solution.

4. The method of inhibiting the clouding of

liquid potassium soaps during storage in glass containers which comprises removing the insoluble calcium and magnesium compounds by filtering the soap solution, and thereafter adding to the soap solution about 1% to 2% of sodium hexametaphosphate based on the total soap content of the solution.

5. The method of inhibiting the clouding of liquid potassium soaps during storage in glass containers which comprises permitting the solution to stand at a temperature of about 40° to 45° F., removing the insoluble calcium and magnesium compounds by filtering, and adding to the clarified soap solution about 1% to 2% of sodium hexametaphosphate based on the total soap content of the solution.

HARRY L. ROSCHEN.
